HOLDER FOR LIPSTICKS AND THE LIKE

Walton B. Crane, West Los Angeles, Calif.

Application August 22, 1942, Serial No. 455,687

2 Claims. (Cl. 206—56)

This invention relates generally to holders for lipsticks, eyebrow pencils and similar soft pasty cosmetics, and particularly to holders of the type in which the cosmetic is adapted to be ejected and retracted by relative rotation of two parts of the holder.

Prior lipstick holders have generally been constructed of metal, though there have been some efforts to design a suitable holder which can be constructed of plastic materials. For various reasons these efforts have not met with great success, plastic construction presenting various problems which are foreign to metal construction, and which have not heretofore been entirely solved. Among these problems is the provision of a device which will not be excessively bulky, which will operate freely, which may be easily and quickly assembled, and which lends itself to plastic molding methods.

It is accordingly the general object of the invention to provide a lipstick holder of the ejecting type which overcomes in a satisfactory manner the various problems incident to plastic construction.

One problem in both metal and plastic holders which employ a slip cap is to prevent the possibility of placing the cap on the holder while the lipstick is in partially ejected position, or the further possibility of partially ejecting the lipstick while the cap is in place on the holder, either of which operations results in engagement of the lipstick with the inner end of the cap, with consequent soiling of the inside of the cap. A further object of the invention is accordingly the provision of a lipstick device in which this condition cannot occur.

Further particular objects of the invention have to do with the provision of a lipstick holder device of a simple plastic construction, which is easily and freely operable, easy of assembly, and with the provision of a novel and improved method of assembling a lipstick holder of the type disclosed.

Further objects, features, and accomplishments of my invention will appear in the course of the following detailed description of one present preferred embodiment thereof, reference for this purpose being had to the accompanying drawing, wherein:

Fig. 1 is a perspective view of the lipstick holder of the invention, with the slip cap removed;

Fig. 2 is a longitudinal medial section through the holder, the slip cap being in position;

Fig. 3 is a view taken as indicated by broken line 3—3 of Fig. 2, the slip cap being removed;

Fig. 4 is a transverse section taken on line 4—4 of Fig. 2;

Fig. 5 is a view showing a step in the assembly of the cosmetic holder with the ferrule;

Fig. 6 illustrates the next step in the assembly of the cosmetic holder with the ferrule;

Fig. 7 is an exploded view illustrative of the assembly of the holder; and

Fig. 8 is a view similar to a portion of Fig. 2, but showing a modification.

In the drawing, numeral 10 designates generally a cylindrical casing or barrel, preferably, though not necessarily, formed of plastic. Slidably received within this casing or barrel 10 is the cosmetic cup or carrier 11, also preferably formed of plastic. Cup 11 has oppositely projecting pins or lugs 12, which project through diametrically opposite longitudinal slots 13 formed in barrel 10. The pins or lugs may be formed integrally with the cup, though not necessarily so, the essential, broadly speaking, being merely that there be pins or lugs 12 extending from the two opposite sides of the cup. The cup 11 will of course be understood to be adapted to support the usual lipstick or other cosmetic, designated at L in Fig. 2.

In the preferred and here illustrated construction, the longitudinal slots 13 in barrel 10 extend from points near the forward end of the barrel to the rearward end thereof, the slots 13 thus being open ended at the rearward end of the barrel to receive the projections 12 of cup 11 at the time of assembly.

Surrounding and longitudinally movable on the barrel 10 is a ring 15, also preferably formed of plastic, and which is preferably of about the same length as cup 11, and has a straight bore of just slightly greater diameter than the outside diameter of barrel 10, so as to provide a free turning and sliding fit. This ring is formed and functions as a nut element, its inside surface being here shown as provided with raised spiral thread elements 16, preferably of relatively coarse pitch, and the exterior surface of barrel 10 being formed with complementary thread elements in the form of cooperating spiral grooves 17, which extend preferably from its base end to the ends of the slots 13, as shown. Of course by simple reversal, the raised spiral thread elements 16 might be formed on the barrel 10, and the spiral grooves in ring 15. It is of course evident that while I may preferably employ double threads, as here indicated, this is not at all limitative on the invention. Rotation of ring 15 relatively to barrel 10 effects translation of the ring along the barrel,

the ring functioning as a nut member which is translated longitudinally of the barrel as it is rotated.

The aforementioned lugs 12 on opposite sides of cup 11 extend to a diameter greater than the inside diameter of ring 15, and enter a circumferential groove 20 formed inside said ring, so as to engage the two oppositely facing annular shoulders 21 defining the sides of said groove, whereby cup 11 will be translated longitudinally of barrel 13 along with ring 15. Thus ring 15 rotates relatively to cup 11, whose rotation relatively to the ring is prevented by the engagement of projections 12 with slots 13 in barrel 10, so that projections 12 ride around groove 20 as the ring is rotated, while at the same time the component of movement of the ring longitudinally of barrel 10 is imparted to cup 11 by reason of engagement of cup projections 12 with one or the other of annular shoulders 21 of groove 20. Preferably, the circumferential groove 20 inside ring 15 is at about the middle of the latter, and the thread elements 16 extend only from the bottom of the ring to the groove; actually, the thread elements 16 may be reduced in length until they consist of nothing more than lugs or pins, though better and smoother action is gained by making the elements spiral in form, and of some length, as indicated.

Barrel 10 is provided at its rearward end with an operating head 22, preferably of general disc shape, and of approximately the same or slightly larger diameter as ring 15, and preferably formed of plastic. The inner face of this head 22 is formed with a groove or channel 23 adapted to snugly receive the end of barrel 10. Head 22 is secured tightly on the end of barrel 10 in any suitable manner; assuming the parts to be composed of any of the common types of thermo-plastics, they may be united tightly by touching the end portion of the barrel with a suitable solvent such as acetone before inserting it into groove 23. Preferably, head 22 is formed within groove 23, with pyramidal projections 24 adapted to engage the V-notches 24a at the open ends of barrel slots 13, so as to support the slotted barrel and assure that both of the slots 13 will be of proper and equal widths throughout their lengths. It will be evident that the head 22 affords a stop shoulder for the lower end of the barrel.

A feature of the invention consists of a novel and improved method of assembly of the device, which may be understood readily by reference to Figs. 6, 7, and 8. Cup 11 is first assembled with ring 15 by squeezing the latter so that its width is increased sufficiently to accept the cup 11 with its two lugs 12 (see Fig. 5). The cup is then placed inside the ring and its lugs 12 positioned in alignment with circumferential groove 20, as illustrated in Fig. 5. Release of the pressure on the sides of the ring then causes the latter to spring back to circular shape, whereby the lugs 12 become engaged in groove 20. The cup and ring as thus assembled are then assembled with barrel 10 by inserting the slotted end of the latter in the annular space between members 11 and 15 and engaging slots 13 with lugs 12, as will be easily understood. The V-formations at the open ends of the slots to facilitate "finding" the lugs 12, and after inserting the end of the barrel in between the cup and ring, the ring is then simply turned relatively to the barrel as it is moved onto the barrel, the slots first finding the lugs 12, and when the threaded portion of the ring reaches the threaded portion of the barrel, the threads readily start and the ring screws properly onto the barrel. The

cup and ring having thus been assembled with barrel 10, the operating head 22 may then be mounted on the end of the barrel in the manner already described.

5 The lipstick is ejected or retracted by grasping and relatively rotating operating head 22 and nut ring 15. This results in movement of the ring longitudinally along barrel 10, with corresponding translation of cup 11 and the lipstick L. Fig. 2 shows the holder in fully retracted position; and with the slip cap 25 mounted thereon, the cap being understood to be provided with a frictional fit on the barrel, or with any other suitable retaining arrangement. Attention is directed to the fact that the slip cap is made 10 long enough that its open end 26 comes immediately adjacent to or against the end of ring 15 when in the closed position of Fig. 3, and that in such position, the end of lipstick L is somewhat spaced from the closed end of the cap. It 15 will now be apparent that if the ring 15 be rotated while the cap is in such position, the ring will engage the cap and push the latter ahead, so that it is impossible for the end of the lipstick 20 to engage the inside of the cap. Similarly, if the cap is placed on the device with the lipstick in partially ejected position, it will engage ring 15 before its closed end strikes the end of the lipstick. Thus complete protection 25 is provided against soiling the cap by the end of the lipstick. The device is exceptionally freely operable, the short ring 15 sliding and turning on the barrel without sticking, and the threads giving a smooth and free operating characteristic. The cup lugs slide freely in the ring groove 30 20, and there is no undesirable friction between any of the working parts.

35 Fig. 8 shows a modification, in which the two oppositely facing annular shoulders on the operating ring 15a are formed on the ends of the ring, as at 21a and 21b, preferably by annularly undercutting the ends of the ring, as illustrated, and in which the cup 11a has one upper lug 12a and one lower lug 12b projecting through the 40 slots 13a of barrel 10a and engaging the two shoulders 21a and 21b. It will be evident that 45 this form of the invention operates the same as that previously described. The advantage is gained that the cup is more readily assembled with the ring, it not being necessary to elongate the latter in assembly, since the cup may be readily inserted simply by tilting it somewhat, as will be perfectly obvious.

50 It will of course be understood that the drawings and description are for illustrative purposes only, and that various changes in design, structure, and arrangement may be made without departing from the spirit and scope of the invention or of the appended claims.

60 I claim:

65 1. In a cosmetic holder, the combination of a barrel having an open forward end and having a longitudinal slot extending from a point near its said forward end through its rearward end, a cosmetic cup inside said barrel, a sleeve relatively rotatable around and slidably along said barrel, a circumferential groove inside said sleeve and spaced substantially from both ends thereof, a lug projecting from the side of said cup through said longitudinal slot in said barrel into said circumferential groove in said sleeve, a head on the rearward end of said barrel, a raised thread element inside said sleeve located exclusively between said circumferential groove and 70 the end of said sleeve nearest said head, and a

spiral thread groove sunk in the outer surface of said barrel and engaged by said thread element.

2. In a cosmetic holder, the combination of a barrel having an open forward end and having a pair of diametrically opposed longitudinal slots extending from points near its said forward end through its rearward end, a head on said rearward end of said barrel, a cosmetic cup inside said barrel, a sleeve relatively rotatable around and slidable along said barrel, a circumferential groove inside said sleeve and spaced substantially

from both ends thereof, lugs projecting from opposite sides of said cup through said longitudinal slots in said barrel and into said circumferential groove, two diametrically opposed spiral thread grooves sunk in the outer surface of said barrel, and a pair of diametrically opposed raised spiral thread elements formed inside said sleeve exclusively between said circumferential groove and the end of said sleeve nearest said head engaging in said spiral grooves in said barrel.
